UNITED STATES PATENT OFFICE.

HAWLEY E. DAINES, OF ORION, MICHIGAN, ASSIGNOR TO GAS OIL STOVE COMPANY, OF DETROIT, MICHIGAN, A CORPORATION OF MICHIGAN.

HYDROCARBON-BURNER.

1,254,209.

Specification of Letters Patent. Patented Jan. 22, 1918.

Application filed September 27, 1916. Serial No. 122,338.

To all whom it may concern:

Be it known that I, HAWLEY E. DAINES, citizen of the United States, residing at Orion, county of Oakland, State of Michigan, have invented a certain new and useful Improvement in Hydrocarbon-Burners, and declare the following to be a full, clear, and exact description of the same, such as will enable others skilled in the art to which it

10 pertains to make and use the same, reference being had to the accompanying drawings, which form a part of this specification.

My invention relates to an improvement in hydrocarbon burners, shown in the accompanying drawings and more particularly pointed out in the following specification and claims.

One of the principal objections to the usual hydro-carbon burner upon opening the 20 valve controlling the delivery of oil to the burner is that the oil flowing rapidly into the vaporizing chamber floods the "lighting ring" or wick adjacent to the inlet orifice, and upon lighting the "ring" it burns unevenly for a time, "flaming" adjacent to the 25 inlet pipe until the oil is uniformly distributed throughout the wick and the flame brought under control.

One of the objects therefore of this invention is to overcome this objectionable feature by delivering the fuel oil through an annular passageway having a perforated wall adjacent to and concentric with the vaporizing chamber housing the lighting ring, 30 whereby the oil may be simultaneously and uniformly delivered to the ring so that upon lighting the oil stored in the latter it may instantly present a flame of uniform height and intensity that the gas generated thereby 35 may be of a constant uniform character and insuring throughout an intense even flame.

With the foregoing and other objects in view which will hereafter appear as the description proceeds, the invention resides in 40 the combination of parts and in details of construction hereinafter more fully described.

In the drawings accompanying this specification:—

45 Figure 1 is a side elevation of a hydrocarbon burner with parts broken away.

Fig. 2 is a central vertical sectional view through the same.

Fig. 3 is a horizontal sectional view on 50 line 3—3 of Fig. 2.

Fig. 4 is a vertical sectional view of an enlarged detail of the annular feeding channel and vaporizing chamber.

Referring now to the letters of reference placed upon the drawings:

A, denotes an inner cylindrical chimney having apertures *a*, to admit air to the flame between it and the outer chimney B, which is also perforated at *b*, for the passage of air.

C, indicates an annular vaporizing chamber having offset portions C', C', forming ledges upon which the respective chimneys A, and B, are supported when in position.

C', denotes a plurality of perforations in the outer wall of the vaporizing chamber for the passage of liquid fuel into the chamber.

D, indicates an asbestos or other lighting ring, supported in a suitable collar D', adapted to be contained in the vaporizing chamber.

E, designates an annular ring or channel member, surrounding the perforated wall of the vaporizing chamber for the simultaneous delivery of liquid fuel to the entire surface of the latter;—the ring being preferably brazed to the wall of the vaporizer that it may be an integral part thereof, in order to avoid the escape of gas between the abutting walls resulting from the increase of temperature due to the proximity of the ring to the vaporizing chamber.

F, denotes a pipe for the delivery of liquid fuel to the ring E, and F' is a suitable valve for controlling the delivery of fuel through the pipe.

G, indicates the usual annular shield surrounding the burner to guard it from air currents that might affect the flame.

Having indicated the several parts by reference letters the construction and operation of the device will be readily understood.

Upon opening the valve controlling the delivery of oil to the ring E, the oil will immediately flow completely around the ring, entering the vaporizing chamber through the relatively small apertures in the wall of the latter, which serves as a "baffle" plate, to insure uniform distribution of the fuel over the entire surface of the lighting ring housed within vaporizing chamber. To ignite the oil in the vaporizing chamber a torch or lighted match is applied.

plied to the ring,—producing an instantaneous and complete annular flame of uniform height throughout the vaporizing chamber and thereby effecting a complete and uniform vaporization of the oil subsequently delivered thereto, and thus avoiding the usual “flaming” incident to initial ignition of hydro-carbon burners of this character.

10 Having thus described my invention, what I claim is:—

1. In a hydro-carbon burner, a vaporizing chamber including inner and outer walls offset to form spaced ledges, the outer wall of the chamber having relatively small apertures, inner and outer cylindrical chimneys seated on the respective ledges of the vaporizing chamber walls, a fuel channel surrounding the vaporizing chamber with its open side rigidly secured to the outer wall of the vaporizing chamber with the upper free edge of the channel disposed immediately under the ledge of the outer wall of the chamber, the chamber and channel having communication through said relatively small apertures in the outer wall of the chamber whereby the escape of unpleasant

odors from the channel incident to the heating of the oil is prevented.

2. In a hydrocarbon burner, a vaporizing chamber including inner and outer walls offset to form spaced ledges, the outer wall of the chamber having relatively small apertures, inner and outer cylindrical chimneys seated on the respective ledges of the vaporizing chamber walls, a seamless fuel channel substantially semi-circular in cross section surrounding the vaporizing chamber with its open side rigidly secured to the outer wall of the vaporizing chamber with the upper free edge of the channel disposed immediately under the ledge of the outer wall of the chamber, the chamber and channel having communication through said relatively small apertures in the outer wall of the chamber whereby the escape of unpleasant odors from the channel incident to the heating of the oil is prevented.

In testimony whereof I sign this specification in the presence of two witnesses.

50 HAWLEY E. DAINES.
